United States Patent

Des. 236,519
Patented Aug. 26, 1975

236,519

STILT

Peter F. Boyce, 118 E. Rio Grande Ave.,
Wildwood, N.J. 08260

Filed Oct. 12, 1973, Ser. No. 405,793

Term of patent 14 years

Int. Cl. D21—01

U.S. Cl. D34—14 E

FIG. 1 is a front elevational view of a stilt showing my new design;

FIG. 2 is a rear perspective view thereof;

FIG. 3 is a top perspective view thereof;

FIG. 4 is a bottom plan view thereof;

FIG. 5 is a left perspective view thereof; and

FIG. 6 is a right perspective view thereof.

I claim:

The ornamental design for a stilt, as shown and described.
